CENTRALIZED TRAFFIC CONTROLLING
SYSTEM FOR RAILROADSWinfred T. Powell, Rochester, N. Y., assignor to
General Railway Signal Company, Rochester,
N. Y.

Application May 19, 1934, Serial No. 726,525

24 Claims. (Cl. 246—3)

This invention relates to centralized traffic controlling systems for railroads and it more particularly pertains to the communication part of such systems.

5 By means of the centralized traffic controlling system contemplated by the present invention, switches and signals at field stations along a railroad system are under the supervision and control of an operator at a central control office so that they can be positioned in accordance with the required traffic over the stretch of track equipped with the system. Likewise, the conditions of the various traffic controlling devices, such as the switch positions, the clear and stop 10 signal indications and the like, are transmitted to the control office to provide the operator with such information as may be necessary for the proper governing of train movements.

The present invention more particularly relates to a centralized traffic controlling system wherein the supervision of the traffic governing devices and the indication of their conditions are accomplished over a communication system having only two line wires. These two line wires 20 serve to connect the control office with certain of the field stations. The present invention is more particularly directed to a traffic controlling system in which the distance between certain of the field stations and the control office is such that it is impractical to transmit impulses from the control office to certain distant field stations 25 because of the length of the line circuit.

The present invention contemplates the use of one or more repeater stations for repeating the impulses both ways over the communication system. In addition to the repeater station or stations, regular stations are connected to the communication system either between the control office and the first repeater station or beyond the 30 repeater station.

The apparatus at the control office and at each field station is organized to be responsive to different series of impulses arranged in distinctive combinations in accordance with the character of the messages desired to be transmitted for selecting stations for out-bound messages, for registering stations for in-bound messages and for the transmission of the required conditions after the station has been selected or registered. Each 35 series of impulses causes the apparatus at the control office and at all field stations to operate through a cycle of operations.

More specifically, a line battery or other suitable source of current is located in the control office and a similar source of current is located 40

at each field station. The control office operator may cause the transmission of a series of positive and negative impulses in various combinations from the source located in the control office to operate the system through a control cycle of 5 operations. During a control cycle the regular field stations between the control office and the first repeater station (including the repeater station) are responsive to primary impulses supplied from the control office battery and the regular field stations beyond the repeater station are 10 responsive to secondary impulses supplied from the repeater station battery.

Likewise any field station may cause the transmission of a series of positive and negative impulses in various combinations from the source of current located at the station which is transmitting. If this is the repeater station nearest the control office or a regular station between this repeater station and the control office the 15 impulses are supplied from the station which is transmitting. If the transmitting station is beyond the repeater station then the impulses between the transmitting station and the repeater station are supplied from the source of current 20 at the transmitting station, these impulses being recorded at the repeater station and repeated to the control office from the source of current 25 at the repeater station.

In other words, during a cycle for the transmission of controls the control office impulses the line circuit which extends to the first repeater station with the control office battery and the repeater station repeats these impulses over the line circuit extending beyond the repeater station with its battery. For an indication cycle initiated at a station beyond the repeater station, the transmitting station impulses the line 30 extending to the repeater station from the transmitting station battery and the repeater station 35 repeats these impulses to the control office from the repeater station battery.

The impulses transmitted from the control office and from a field station are of substantially equal duration and are separated by substantially equal time spaces. They are made distinctive during transmission in either direction by reason of their polarity.

Step-by-step means located at the control office and at each field station operate in response to 45 the impulses irrespective of their character. During a control cycle one of two distinctive messages or controls may be transmitted on each step by reason of the distinctive character (polarity) of the corresponding impulse applied to 50 55

the line circuit. During an indication cycle one of two distinctive messages or indications may be transmitted on each step by reason of the distinctive character (polarity) of the corresponding impulse applied to the line circuit. In other words, it is possible to transmit controls with a choice of two on each step of a control cycle and to transmit indications with a choice of two on each step of an indication cycle. Since the system is of the simplex type it operates through separate cycles for the transmission of controls and indications.

Other features of novelty embodied in the present invention reside in the manner in which a line circuit connects the control office with a plurality of stations up to and including a repeater station and separate line circuit connects the repeater station to a plurality of other stations. The arrangement whereby proper synchronism is obtained during out-bound and in-bound cycles of transmission, with these impulses repeated at the repeater station during these cycles also is an important feature of the invention.

A further feature of the present invention resides in the manner in which the field stations are prevented from transmitting indications to the control office from more than one station at any one time.

Another feature of the present invention resides in the manner in which the stepping relay bank at the repeater station, which responds to impulses from the control office or from a distant regular station, repeats these impulses to distant stations or to the control office respectively.

These characteristic features of the present invention thus briefly stated will be explained more in detail in the following description of one embodiment of the invention and various other features, functions, and advantages of a system embodying the invention will be in part pointed out and in part apparent as the description progresses.

In describing the invention in detail reference will be made to the accompanying drawings in which similar parts throughout the several views are designated by similar reference characters, generally made distinctive either by distinctive exponents representative of their location or by reason of preceding numerals representative of the order of their operation and in which:—

Fig. 1A illustrates in a diagrammatic manner the line circuit and the more directly associated apparatus in a system embodying the present invention;

Figs. 1B, 1C, 1D, and 1E are schematic circuits showing the connections of the batteries to the line circuits under various conditions, which will be explained in detail.

Figs. 2A and 2B illustrate the apparatus and circuits of a typical control office arranged according to the present invention;

Figs. 3A and 3B illustrate the apparatus and circuits employed at a typical repeater station in accordance with the present invention;

Fig. 4 illustrates the apparatus and circuits employed at a typical regular field station in accordance with the present invention.

These drawings illustrate a system having a plurality of field stations and a control office. For convenience in the description it is assumed that there is one repeater station between the control office and a regular station, although it will be understood that additional regular stations may be connected between the control office and the repeater station illustrated in Fig. 1A

and that additional regular stations may be connected beyond the regular station illustrated. Similarly additional repeater stations may be provided as dictated by the requirements of practice.

With reference to Fig. 1A, the control office is connected to the repeater station by means of a two wire line circuit comprising a control line and a return line. The repeater station is connected to the regular station by means of a two wire line circuit comprising a control line¹ and a return line¹. The back contact of the lockout relay at the end field station is connected to the return line¹ conductor at this station for providing a closed circuit for the line extending from the repeater station to the end station. Similarly, back contact 150 of relay CK² at the repeater station is connected to the return line for providing a closed circuit for the line between the control office and the repeater station. In this connection it will be understood that, when regular stations are connected between the control office and the repeater station, no back contacts similar to 150 of relay CK² are provided for connecting the control line to the return line normally because such relays are not used at the regular stations. Therefore, the regular stations are connected in series in the line circuit (as indicated by contact 250 of relay LO²), instead of terminating the line circuit as at a repeater station.

Although the embodiment of the present invention illustrates the repeater station and the regular station as having only a single switch and associated signals, it will be understood that the invention is not so limited since any desired number of switches and signals may be arranged to suit the track layout.

For the purpose of simplifying the illustrations and description, various parts and circuits have been shown diagrammatically and certain conventional illustrations have been employed, the drawings have been made more with the purpose in mind to make it easier to understand the principles and mode of operation of such a system rather than with the idea of illustrating the particular construction and arrangement of parts that would be employed in actual practice. Thus the relays and their contacts are illustrated in a conventional manner and symbols are used to indicate connections to the terminals of batteries or other suitable source of electric current instead of showing all of the wiring connections to these terminals.

In some of the drawings, Figs. 2A, 2B, 3A, and 3B, for example, certain relays have been shown in full lines on one drawing and in dotted lines on an adjacent drawing. The relays shown in dotted lines have been given the same reference characters as applied to these relays shown in full lines since they are the same relays and they have been connected by dotted lines extending between the drawings. The relays shown in dotted lines have the circuits of their windings omitted, all of which is for the purpose of simplifying the drawings as much as possible.

The symbols (+) and (−) are employed to indicate the positive and negative terminals respectively of suitable batteries or other sources of direct current. The symbol (CN) is employed to indicate a center or intermediate tap of a battery or other source of direct current, of which the terminals of this source are indicated by the terminals (B+) or (B−).

Control office equipment.—The control office

equipment includes a biased-to-neutral, polar line relay F which repeats the impulses applied to the line circuit by battery B in the control office or by battery B¹ at the repeater station. 5 Relay F actuates its polar contacts to the right when the control office applies impulses of (+) polarity to the control line with current from battery B and when the repeater station applies (−) impulses to the control line conductor from battery B¹. Neutral line repeating relay FP, of the quick acting type, repeats the impulses applied to relay F irrespective of their polarity. Slow 10 acting relays SA and SAP are used to define the bounds of an operating cycle. They are picked up in sequence at the beginning of a cycle and dropped in sequence at the end of a cycle. Due 15 to their slow acting characteristics they remain picked up during the intermittent operation of relay FP.

20 A cycle determining relay S of the neutral type is normally deenergized to provide a closed line circuit at the control office and to connect the control office battery to the line circuit when it is energized during a control cycle. The particular polarity applied to the line circuit at the control office for the transmission of controls is determined by code selecting relay CS. Cycle 25 checking relay CK remains down during the transmission of controls and is picked up during a cycle for the transmission of indications. Impulse relays E and EP time the length of the impulses and the spaces between impulses, these relays operating in response to the stepping operation of the system.

30 A suitable step-by-step relay bank is employed including relays VP, 1V, 2V, 3V, and LV. Relays 1V, 2V, 3V, and LV take their steps during the deenergized or "off" periods of the line circuit and relay VP shifts its position during the energized or "on" periods of the line circuit. When the stepping relays are picked up they are stuck up until the end of the cycle. Half-step relay VP is picked up and dropped during alternate "on" periods of the cycle.

35 The control office also includes a starting relay STR which is momentarily energized at the start of a control cycle and which remains down during an indication cycle. The office is provided with a suitable control machine which includes a miniature track diagram to 40 representative of the actual track layout in the field, together with control levers and buttons which are manually operable to obtain the desired control. As typical of such levers, switch machine control lever SML and starting button SB have been indicated in Fig. 2A.

45 A similar starting button is provided for each group of control levers and is associated with a particular field station, so that the positioning of the control levers for a particular station results in the transmission of controls to that station following the operation of the associated starting button. Switch machine lever SML is typical of other levers which are ordinarily provided, such as signal control levers but these latter levers have been omitted since a description of the operation controlled by lever SML is typical of the control by the additional levers.

50 Instead of showing the actual circuits and means associated with the several starting buttons for accomplishing the initiation of the system and for allowing the transmission of controls to only one station at a time, such control has been merely indicated by a dotted line connecting button SB with relays SR and CD. The

means which may be provided to obtain these results includes storing relay SR and code determining relay CD, one of each for each starting button. The relays SR and CD for a particular station are so interlocked with the other SR and CD relays for other stations that only one CD relay can be energized at any one time irrespective of the number of SR relays which are picked up. Such an arrangement of SR and CD relays has been completely shown in prior applications 10 such, for example, as in the pending application of N. D. Preston et al. Ser. No. 455,304 filed May 24, 1930, corresponding to Australian Patent 1501 of 1931. It is believed, however, that the above discussion of the SR and CD relay operations is sufficient for an understanding of the operation of the present invention.

55 As typical of the station registering means in the control office, pilot relays 1PT and 2PT selectively actuated on the first two steps of the 20 cycle have been illustrated. For illustrating station selection by a particular combination of positions of the two pilot relays, a station relay ST has been illustrated. It will be understood that additional pilot relays can be provided for additional steps for individually registering a larger number of stations when required.

25 For the purpose of illustrating the storing of indications from a registered station, indicating storing relay IR has been illustrated as being operated on the third step of the cycle. This relay is provided with a circuit for operating the track occupancy lamp OS. It will be understood that additional indication storing relays 30 may be provided for operating additional devices 35 of which lamp OS is typical.

30 *Repeater station equipment.*—With reference to Figs. 3A and 3B, the repeater station includes a track switch TS¹ which is operated by a switch machine SM¹ of any suitable type. The position 40 of the track switch is repeated by the usual switch repeating relay which is not shown in the present embodiment. The occupied and unoccupied condition of the track section is indicated by track relay T¹ being energized to indicate 45 the unoccupied condition of the track and de-energized to indicate the occupied condition of the track with which it is associated.

45 The traffic over the track switch is governed in accordance with the signals illustrated but 50 the control of these signals is not shown since this control may be accomplished in a similar manner to the control of the switch machine by means of polar impulses received after the station is selected.

55 The selection of the illustrated station for controls is accomplished by pilot relays 1PT¹ and 2PT¹ which are selectively positioned on the first two steps of the control cycle in accordance with the polarity of the impulses transmitted 60 from the control office. Change relay CH¹ is for the purpose of initiating the system into a cycle of operations from this station when a change takes place which requires the transmission of new indications. The circuits for controlling 65 this relay have been omitted, since it is well understood how such a relay is deenergized by the shifting of contacts on the track relay or the switch repeating relay.

70 The communication part of the system includes 70 a biased-to-neutral, polar relay F¹ and its repeating relays FP¹, SA¹ and SAP¹ operating in synchronism with and in a similar manner as corresponding relays in the control office.

75 Two checking relays CK¹ and CK² are pro- 75

vided, the first being picked up throughout a control cycle and the second being picked up throughout an indication cycle. Code selecting relay CS¹ selects the polarity of the impulses applied to the line circuit leading to the more distant stations during a control cycle and also for selecting the polarity of the impulses applied to the line circuit leading to the control office during an indication cycle.

10 Lockout relay LO¹ is provided for the purpose of selecting the circuits for positioning code selecting relay CS¹ in accordance with the location from which impulses are transmitted. In other words, when the repeater station is transmitting to the control office, relay LO¹ is picked up so that relay CS¹ is positioned in accordance with the code jumper connections and the indications to be transmitted. If relay LO¹ is down relay CS¹ is positioned in accordance with 15 the positions of line relay F² which responds to the impulses transmitted from a station farther out the line.

The repeater station is provided with a bank of stepping relays 1V¹, 2V¹, 3V¹, LV¹ and associated half step relay VP¹. The stepping relay bank takes one step for each "off" period and the half step relay is shifted during each "on" period in synchronism with corresponding relays in the control office.

30 *Regular field station equipment.*—With reference to Fig. 4, the regular field station includes a biased-to-neutral, polar line relay F³ and its repeating relays FP², SA² and SAP² operating in a similar manner to corresponding relays in the control office. This station includes a bank of stepping relays 1V², 2V², 3V² and the associated half step relay VP² operating in synchronism with corresponding relays in the control office. It is to be understood that synchronism referred 35 to does not mean that the relays at the regular station are energized and deenergized at exactly the same time as corresponding relays at the repeater station or at the control office, since there may be other relay operations intervening 40 to delay the operations at this station. This is because the impulses are repeated at the repeater station but synchronism is approximately attained.

50 Checking relay CK³ is picked up throughout a control cycle and lockout relay LO² is picked up throughout an indication cycle initiated at this station. Code selecting relay CS² selects the polarity of the impulses applied to the line¹ at this station in accordance with the code combination to be transmitted. Change relay CH² is for the purpose of initiating the system in response to a change in condition at this station which requires the transmission of indications.

55 For the purpose of selecting this station for the transmission of controls thereto, pilot relays 1PT² and 2PT² are illustrated as being selectively positioned on the first two steps of the cycle. For the purpose of illustrating the transmission of controls to a selected station, switch machine control relay SMR² is illustrated as being selectively operated on the third step of the cycle when the pilot relays are in proper positions for selecting this station.

70 Track switch TS² is illustrated as being controlled by switch machine SM² and the occupied and unoccupied condition of the illustrated track section is repeated by track relay T² in the usual manner. The control of the signals at this station has not been shown in detail, since the

control of the switch machine may be considered typical of the manner in which additional steps of the cycle function to control signals in response to additional impulses. Lockout relay LO³ at the end station is illustrated in the upper right hand corner of Fig. 4 for the purpose of showing that the line circuit is normally closed at the end station.

75 It is believed that the invention will be best understood by setting forth in the following description various typical operations in detail.

General operation

The system of the present invention is normally in a condition of rest from which it may be initiated into a cycle of operations either from the control office or from any of the field stations whenever there are new controls or new indications respectively to be transmitted.

80 Although new controls and indications may occur simultaneously, the system is so arranged that only controls or indications may be transmitted during any one particular cycle. In case new controls and indications become ready for transmission simultaneously, the system is so arranged that the resulting cycle is for the transmission of indications. As long as there are indications awaiting transmission, the system functions to transmit these indications before permitting the transmission of controls from the control office. In other words, indication conditions are superior to control conditions when both exist with the system in its normal condition.

85 While the system is in its normal condition the line circuit is deenergized. The energization of the line circuit with (+) potential during the conditioning period at the start of a cycle renders the succeeding cycle effective for the transmission of controls. The energization of the line circuit with a (−) potential during the conditioning period at the beginning of a cycle renders the succeeding cycle effective to transmit indications.

90 For convenience in describing the present invention a (+) primary impulse applied to the control line circuit (see Fig. 1A) will be considered as an impulse which causes current to flow from left to right in the control line. Similarly, a (+) secondary impulse applied to the control line¹ circuit will be considered as causing current to flow from left to right in the control line¹. During an indication cycle, a (−) impulse applied to the line circuit from the regular station will be considered one which causes current to flow from right to left in the control line¹. Similarly, a (−) impulse applied to the line circuit from the repeater station during an indication cycle will be considered as causing current to flow from right to left in the control line.

95 *Normal at rest condition.*—With the system in its normal condition, the line circuit extending from the control office to the repeater station and the line circuit extending from the repeater station to the regular station are both deenergized. With relay S in the control office deenergized, a return path is provided for current in the control line so that this line can be energized with (+) or (−) impulses from the repeater station when its relay CK² is picked up. With relay CK² deenergized, a return path is provided for current in the control line so that this line can be energized from the control office when relay S is picked up. Similarly, with relay LO² at the regular station deenergized, a return path is provided for current

in the control line¹ so that this line can be energized with (+) or (−) impulses from battery B¹ as long as relay CK¹ is energized. With relays CK¹ and LO¹ deenergized, a return path is provided for current in the control line¹ so that this line can be impulsed with (+) or (−) impulses from the regular station when its relay LO² is picked up.

Schematic sketches Figs. 1B, 1C, 1D, and 1E show the various fundamental line circuit connections during various conditions of the communication system. For example, Fig. 1B indicates the connections of batteries B, B¹, and B² in the control office, the repeater station and the regular station respectively, to show that normally there is no flow of current in either line circuit. Fig. 1C indicates the connections of the batteries to the line circuits during the transmission of controls and it will be noted that current from battery B in the control office flows through line relays F and F¹, while current from battery B¹ at the repeater station flows through line relays F² and F³.

It will be understood that the reference characters associated with the line relays in these schematic drawings refer to the line relays having the same reference characters in the other figures. It will also be understood that the batteries shown are reversibly connected to the line circuits for providing (+) and (−) energization.

Fig. 1D indicates the conditions of the line circuits when indications are being transmitted from the repeater station to the control office. Under this condition line relays F and F¹ are energized from battery B¹ at the repeater station, with battery B in the control office connected to the line circuit by only one terminal so that the line is not energized from the control office battery. Similarly, the line circuit extending outward from the repeater station is not energized, since only one terminal of each battery B¹ and battery B² is connected to this line. The interruption or break in the battery circuit is provided under this condition at back contact 153 of relay LO¹ since this relay is picked up.

Fig. 1E indicates the condition of the line circuits when indications are being transmitted from the regular station to the control office. Under this condition the control office battery is not effective to energize the control line circuit since only one of its terminals is connected thereto. The repeater station battery B¹ is effective to energize the control line circuit and the regular station battery B² is effective to energize the control line¹ circuit. It will be noted that, although the control line is connected to the return line¹ with the terminal of each of the batteries B¹ and B² connected to the circuit, there is no interference or faulty operation caused by this connection of the two line batteries because the tie between the two line circuits consists of only a single conductor with no return path.

Relay CS in the control office (see Fig. 2A) is normally energized for positioning its polar contacts to the right over a circuit which extends from (B+), back contacts 14, 15 and 16 of relays 1V, 2V, and 3V respectively and winding of relay CS, to (CN). At the repeater station, track relay T¹ is normally energized, since it is assumed that the associated track section is unoccupied. Change relay CH¹ is normally energized, since it is assumed that no change has taken place at this station since the last cycle of operation. At the regular station track relay T² is normally energized, since it is assumed that the associated

track section is unoccupied. Relay CH² is normally energized, since it is assumed that no change has taken place at this station since the last cycle. Relay CS² is normally energized with its contacts positioned to the left over a circuit extending from (B−), back contacts 253, 254 and 255 of relays 1V², 2V², and 3V² respectively, back contact 256 of relay CK³ and winding of relay CS², to (CN).

Manual start.—It will first be assumed that the operator in the control office desires to move track switch TS¹ at the repeater station from its normal locked position to its reverse locked position. It will be assumed that the repeater station responds to a code combination of (+) and (−) on the first two steps respectively of the communication system. It will also be assumed that the track switch is operated to its reverse position in response to a (−) impulse on the third step of the system.

With the system in its normal condition, the actuation of starting button SB in the control office is effective to pick up relays SR and CD. The picking up of relay SR initiates the system into a cycle of operations and the picking up of relay CD determines the station selecting code and the controls to be transmitted over the line circuit. It will be understood that the storing relays such as relay SR can be picked up at any time the corresponding starting buttons are actuated, but only one code determining relay such as relay CD can be energized at one time and only while the system is in its normal condition.

The picking up of relay SR closes a circuit for picking up relay STR extending from (+), front contact 17 of relay SR, back contact 18 of relay SAP and winding of relay STR, to (−). The picking up of relay STR closes a circuit for picking up relay S which extends from (+), front contact 19 of relay STR, back contact 20 of relay CK 40 and winding of relay S, to (−). The picking up of relay S closes a stick circuit for itself extending from (+), back contact 21 of relay SAP, back contact 22 of relay CK, front contact 23 and winding of relay S, to (−). Relay S remains stuck up during the control cycle because relay SA closes its front contact 24 before relay SAP opens its back contact 21 and because relay CK does not pick up its back contact 22 during such a cycle.

The picking up of relay S closes a circuit for energizing the control line circuit with a (+) impulse which extends from the (+) terminal of battery B, contact 10 of relay CS in its right hand position, front contact 11 of relay S, winding of relay F, back contact 12 of relay EP, control line conductor, winding of relay F¹, back contact 150 of relay CK², return line conductor and contact 13 of relay CS in its right hand position to the (−) terminal of battery B. This energization of the control line circuit positions relays F and F¹ to the right.

This marks the beginning of the conditioning "on" period. Relay FP is picked up over a circuit extending from (+), contact 25 of relay F in its right hand dotted position and winding of relay FP, to (−). Relay FP closes a circuit for picking up relay SA which extends from (+), front contact 26 of relay FP and winding of relay SA, to (−). Relay SA closes a circuit for picking up relay SAP which extends from (+), front contact 27 of relay SA and winding of relay SAP, to (−). Relay SAP closes a circuit for picking up relay VP which extends from (+), front contact 30 of relay SAP, front contact 31 75

of relay FP, back contacts 32, 33 and 34 of relays 3V, 2V and 1V respectively and winding of relay VP, to (-). Relay VP closes a temporary stick circuit for itself extending from (+), front contact 30 of relay SAP, front contact 36 of relay VP and over the remainder of the previously described pick up circuit to the winding of relay VP.

The picking up of relay VP closes a circuit for picking up relay E which extends from (+), front contact 24 of relay SA, front contact 21 of relay SAP, front contact 37 of relay VP, back contact 38 of relay 1V and winding of relay E, to (-). The picking up of front contact 39 of relay E extends this circuit to the winding of relay EP for causing this latter relay to be picked up. The picking up of relay SAP deenergizes the circuit of relay STR at back contact 18 and this relay is dropped after a comparatively long interval of time. The picking up of relay EP deenergizes the control line circuit at back contact 12 which marks the beginning of the first "off" period.

Referring to the repeater station, the energization of relay F¹ closes a circuit for picking up relay FP¹ which extends from (+), contact 162 of relay F¹ in its right hand dotted position and winding of relay FP¹, to (-). Relay FP¹ closes a circuit for picking up relay SA¹ which extends from (+), front contact 163 of relay FP¹ and winding of relay SA¹, to (-). Relay SA¹ closes a circuit for picking up relay SAP¹ which extends from (+), front contact 164 of relay SA¹ and winding of relay SAP¹, to (-).

The energization of relay F¹ closes a circuit for picking up relay CK¹ which is effective before relay SA¹ picks up its contacts and which extends from (B+), contact 165 of relay F¹ in its right hand dotted position, back contact 166 of relay SA¹, back contact 167 of relay CK² and upper winding of relay CK¹ to (B-). Relay CK¹ closes a stick circuit for itself extending from (+), back contact 168 of relay SAP¹, front contact 169 of relay CK¹, back contact 170 of relay CK² and lower winding of relay CK¹, to (-). Since relay SA¹ applies (+) to this stick circuit at its front contact 171 before relay SAP¹ picks up its back contact 168, relay CK¹ is maintained energized over its stick circuit throughout this cycle.

The picking up of relays SA¹ and CK¹, with relay F¹ positioned to the right, closes a circuit for positioning relay CS¹ to the right extending from (B+), contact 165 of relay F¹ in its right hand dotted position, front contact 166 of relay SA¹, front contact 172 of relay CK¹ and winding of relay CS¹, to (CN). As will be later described, a circuit is closed at the end of the cycle for positioning relay CS¹ to the right so that the above described circuit is for the purpose of checking or insuring that this relay will have its contacts in their right hand positions at the start of the cycle.

With the contacts of relay CS¹ positioned to the right and with relay CK¹ picked up, a circuit is closed for energizing control line¹ with (+) polarity extending from the (+) terminal of battery B¹, contact 152 of relay CS¹ in its right hand position, front contact 154 of relay CK¹, winding of relay F², back contacts 177, 155, 156, 70 157, and 158 of relays LV¹, 3V¹, 2V¹, 1V¹, and CK² respectively, control line¹, winding of relay F³, back contact 250 of relay LO², back contact 350 of relay LO³ (at the end station), return line¹ and contact 151 of relay CS¹ in its right hand position to the (-) terminal of battery B¹. By

an analysis of the circuits under this condition it will be seen that the line and battery circuits are connected as shown in Fig. 1C. This (+) energization of control line¹ positions the contacts of relays F² and F³ to the right. 5

Relay F³ closes a circuit for picking up relay FP² which extends from (+), contact 257 of relay F³ in its right hand dotted position and winding of relay FP², to (-). Relay FP² closes an obvious circuit at its front contact 258 for 10 energizing relay SA² and relay SA² closes an obvious energizing circuit for relay SAP² at its front contact 259. Before relay SA² picks up its contacts a circuit is closed for picking up relay CK³ which extends from (B+), contact 260 of 15 relay F³ in its right hand dotted position, back contact 261 of relay SA² and lower winding of relay CK³, to (B-). Relay CK³ closes a stick circuit for itself extending from (+), back contact 263 of relay SAP², front contact 264 and upper 20 winding of relay CK³, to (-). This stick circuit is effective throughout the cycle because relay SA² connects (+) to the circuit at its front contact 262 before relay SAP² removes (+) from the circuit at its back contact 263. 25

The pick up and stick circuits of the stepping and half step relays at the repeater station and at the regular station have been omitted because these circuits are exactly the same as for the corresponding relays in the control office. 30 Therefore relays VP¹ and VP² at the repeater station and the regular station respectively are picked up during the conditioning "on" period. During the following description of the operation of the system it will only be mentioned that the 35 stepping relays and the half step relays at the stations operate, since it is obvious that these relays will operate in synchronism with corresponding relays in the control office when their circuits are controlled by the line repeating relays in the 40 manner shown in detail for the control office relays.

It will be noted that the control line is energized slightly in advance of the energization of the control line¹ due to the fact that, after the 45 energization of the control line, relays F¹ and CK¹ must be energized before the control line¹ is energized so that the operation of the relays at the regular station and relay F² at the repeater station controlled over control line¹ are delayed 50 a short interval of time after corresponding relays controlled over the control line are operated.

Impulsing and stepping operations.—In the above description the operations were explained in detail up to the beginning of the first "off" period, 55 at which time the control line was deenergized by the picking up of relay EP. The deenergization of the control line restores relays F and F¹ to their neutral positions, following which relays FP and FP¹ are deenergized. Relays SA, SAP, SA¹, and SAP¹ are not deenergized during the step-by-step operations because the intermittent operation of the FP relays is at such a rate that the slow acting relays do not have time to drop their contacts. This statement also applies to the slow 65 acting relays at the illustrated regular station as well as all other stations.

The dropping of relay FP closes a circuit for picking up relay 1V which extends from (+), front contact 29 of relay SAP, back contact 40 of 70 relay FP, front contact 41 of relay VP, back contact 43 of relay 2V and winding of relay 1V, to (-). Relay 1V closes a stick circuit for itself extending from (+), front contact 29 of relay SAP, front contact 45 and winding of relay 1V, to 75

(-). A holding stick circuit is closed for relay VP which extends from (+), front contact 30 of relay SAP, back contact 31 of relay FP, front contact 35 and winding of relay VP, to (-).

5 At the repeater station relay 1V¹ is picked up and stuck up over a similar circuit. Likewise at the regular station relay 1V² is picked up and stuck up over a similar circuit. The picking up of relay 1V deenergizes the circuits of relays E and EP at back contact 38. These relays drop after a comparatively long interval of time so that the control line is energized by the dropping of back contact 12 of relay EP. The picking up of relay 1V¹ at the repeater station deenergizes control line¹ at back contact 157 which results in dropping relays F² and F³ to their neutral positions.

The dropping of relay EP in the control office marks the beginning of the first "on" period. The 20 energization of the control line at back contact 12 of relay EP causes relays F, FP, F¹, and FP¹ to be picked up. The picking up of relay FP drops relay VP because its temporary stick circuit is open at back contact 34 of relay 1V and its holding stick circuit is open at back contact 31 of relay FP. A circuit is now closed for picking up relay E which extends from (+), front contact 24 of relay SA, front contact 21 of relay SAP, back contact 37 of relay VP, back contact 48 of relay 2V, front contact 38 of relay 1V and winding of relay E, to (-). Relay E extends this circuit by way of its front contact 39 to the winding of relay EP which picks up its back contact 12.

35 Relay VP¹ at the repeater station is dropped in synchronism with relay VP in the office for energizing the control line¹ over a circuit extending from the (+) terminal of battery B¹, contact 152 of relay CS¹ (assumed to be in its right hand position), front contact 154 of relay CK¹, winding of relay F², back contacts 177, 155, and 156 of relays LV¹, 3V¹, and 2V¹ respectively, front contact 157 of relay 1V¹, back contact 159 of relay CK², back contact 161 of relay VP¹, control line¹ and over the remainder of the previously described line 45 circuit to the (-) terminal of battery B¹, by way of contact 151 of relay CS¹ in its right hand position.

The picking up of back contact 12 of relay EP (above described) deenergizes the control line circuit which marks the beginning of the second "off" period. Relays F, FP, F¹, and FP¹ are dropped. Relay 2V is picked up over a circuit extending from (+), front contact 28 of relay SAP, back contact 40 of relay FP, back contact 41 of relay VP, back contact 44 of relay 3V, front contact 42 of relay 1V and winding of relay 2V, to (-). Relay 2V closes an obvious stick circuit for itself at its front contact 46.

50 Relay 2V¹ at the repeater station is picked up at the same time. The picking up of relay 2V¹ deenergizes the control line¹ circuit at back contact 156 which results in dropping relays F² and F³ to their neutral positions. Relay FP² is now deenergized for causing relay 2V² to be picked up and stuck up. The picking up of relay 2V in the control office deenergizes relays E and EP at back contact 48 so that these relays drop. The dropping of back contact 12 of relay EP energizes the control line circuit.

55 70 This marks the beginning of the second "on" period. Relays F, FP, F¹, and FP¹ are again picked up. Relay VP is now picked up over a circuit extending from (+), front contact 30 of relay SAP, front contact 31 of relay FP, back contact 32 of relay 3V, front contact 33 of relay 2V

and winding of relay VP, to (-). Relay VP closes its temporary stick circuit by way of its front contact 36 and over the previously described circuit to its winding. Relay VP¹ at the repeater station is picked up and stuck up at the same time. 5

The picking up of relay VP¹ energizes the control line¹ circuit by way of front contact 161 of relay VP¹, back contact 160 of relay CK², front contact 156 of relay 2V¹, back contact 155 of relay 3V¹, back contact 177 of relay LV¹, winding of relay F², front contact 154 of relay CK¹ and contact 152 of relay CS¹ (assumed to be in its right hand position) to the (+) terminal of battery B¹. The (-) terminal of battery B¹ is connected to the return line¹ conductor at right hand contact 151 of relay CS¹. Relays F² and F³ are energized over this circuit so that relay FP² picks up at the regular station for picking up relay VP².

The picking up of relay VP at the control office energizes relay E over a circuit extending from (+), front contacts 24 and 21 of relays SA and SAP respectively, front contact 37 of relay VP, back contact 49 of relay 3V, front contacts 48 and 38 of relays 2V and 1V respectively and winding of relay E to (-). The picking up of front contact 39 of relay E extends this circuit to the winding of relay EP which picks up its back contact 12 to deenergize the control line circuit.

The picking up of back contact 12 of relay EP marks the beginning of the third "off" period. 30 Relays F, FP, F¹ and FP¹ are dropped. A circuit is closed for picking up relay 3V which extends from (+), front contact 29 of relay SAP, back contact 40 of relay FP, front contact 41 of relay VP, front contact 43 of relay 2V and winding of relay 3V to (-). Relay 3V closes an obvious stick circuit for itself at its front contact 41. Before relay 3V picks up to deenergize the temporary stick circuit of relay VP, a holding stick circuit for this relay is provided from (+) front contact 30 of relay SAP, back contact 31 of relay FP, front contact 35 and winding of relay VP to (-). Relay 3V¹ at the repeater station picks up in synchronism with relay 3V in the office.

The picking up of relay 3V deenergizes the 45 control line¹ circuit at back contact 155 which drops relays F² and F³. The dropping of relay F³ causes relay 3V² at the regular station to be picked up. The picking up of relay 3V in the control office deenergizes the circuits of relays E and EP at back contact 49 so that these relays drop.

The dropping of back contact 12 of relay EP energizes the control line to mark the beginning of the third "on" period. Relays F, FP, F¹, and FP¹ 55 are again picked up. Relay VP is now deenergized because its temporary stick circuit is open at back contact 32 of relay 3V and because its holding stick circuit is open at back contact 31 of relay FP. Relay VP¹ at the repeater station is similarly 60 dropped. A circuit is now closed for picking up relays E and EP extending from (+), front contacts 24 and 21 of relays SA and SAP respectively, back contact 37 of relay VP, front contacts 49, 48 and 38 of relays 3V, 2V and 1V 65 respectively and winding of relay E, to (-), and through front contact 39 of relay E and the winding of relay EP, to (-).

The dropping of relay VP¹ at the repeater station energizes the control line¹ circuit by way of 70 the previously described circuit through the winding of relay F² which now extends through front contact 155 of relay 3V¹, back contact 159 of relay CK² and back contact 161 of relay VP¹. This picks up relays F² and F³ which results in relay 75

FP² at the regular station picking up to drop relay VP².

The picking up of back contact 12 of relay EP in the control office deenergizes the control line circuit to mark the beginning of the change to normal "off" period. This drops relays F, FP, F¹, and FP¹. The picking up of relays E and EP in response to the dropping of relay VP maintains the control line circuit open for a comparatively long interval of time as will be later described. The comparatively long deenergization of the control line circuit causes relays SA, SAP, SA¹, and SAP¹ to release. The dropping of relay SA deenergizes relays E and EP at front contact 24 so that these relays drop their contacts. The dropping of front contact 24 of relay SA deenergizes the stick circuit of relay S so that this relay is dropped before relay SAP connects (+) to this stick circuit at back contact 21.

20 The dropping of front contact 29 of relay SAP deenergizes the stick circuits of the stepping relays which causes their release. The stepping relays at the repeater station are deenergized in a similar manner. Relay CK¹ at the repeater station is deenergized by the dropping of front contact 171 of relay SA¹. The dropping of relay CK¹ closes a circuit for positioning relay CS¹ to the right before relay SAP drops, which circuit extends from (B+), back contact 173 of relay SA¹, front contact 174 of relay SAP¹, contact 175 of relay F² in its neutral position, back contact 176 of relay LO¹, back contact 172 of relay CK¹ and winding of relay CS¹, to (CN).

In the control office, the dropping of relay FP 35 in response to the change to normal "off" period closes a circuit for picking up relay LV which extends from (+), front contact 29 of relay SAP, back contact 40 of relay FP, back contact 41 of relay VP, front contact 44 of relay 3V and winding of relay LV, to (-). Relay LV closes an obvious 40 stick circuit for itself at its front contact 50. Relay LV has no function in the control office but the pick up circuit is shown to indicate how additional stepping relays are operated when provided and also to indicate how relay LV¹ at the repeater station is picked up in response to the 45 change to normal "off" period. The picking up of relay LV¹ opens the control line¹ circuit at back contact 171 which deenergizes this line for dropping relays F², F³, and FP².

50 Since relay LV in the control office does not control the dropping of relays E and EP, the control line circuit is maintained open for a comparatively long interval of time. Since the picking up of relay LV¹ at the repeater station opens the control line¹ circuit and maintains it open as long as relay LV¹ is stuck up (which is until relay SAP¹ is dropped), the control line¹ circuit is maintained open for a comparatively long interval of time for dropping relays SA² and SAP² 55 at the regular station. The dropping of relay SA² deenergizes the stick circuit of relay CK³ at front contact 262 before relay SAP² energizes this stick circuit at back contact 263, thus resulting in dropping relay CK³. The stepping relays at the regular station are released at the time relay SAP² drops its contacts, because of the deenergization of their stick circuits in a similar manner as indicated in the control office.

70 This places the system in its normal condition, from which it may be initiated in response to a new series of controls or a series of indications requiring transmission. It is believed that the above description of the detailed operation of the stepping relay bank in the control office and

the general description of the stepping relay banks at the illustrated stations is sufficient to convey a complete understanding of the step-by-step and line impulsing operations of the system.

5 *Stored office start conditions.*—In the event that there are one or more storing relays picked up when the system advances into its normal condition, relay STR will be picked up to initiate another control cycle. More particularly, when 10 relay SAP closes its back contact 18 any other SR relay which is picked up will close a front contact similar to 17 for again picking up relay STR. Before relay STR has time to pick up its contacts the deenergization of the stick circuits 15 of the stepping relays at front contact 29 of relay SAP results in the dropping of these stepping relays. With all stepping relays down the circuit is again established through their back contacts 14, 15, and 16 for positioning relay CS to the 20 right. Then when relay STR picks up its contacts relay S will be picked up and stuck up as previously explained for energizing the line circuit with a (+) impulse to initiate another cycle 25 for the transmission of controls.

The picking up of front contact 23 of relay S closes an energizing circuit for relay SAP but before relay SAP has time to pick up its contacts this energizing circuit is opened at back contact 26 of relay FP. Therefore stored office 30 start conditions existing when no field start condition is stored, effects the picking up of relays SA and SAP in sequence in the order named. As will be later described, the existence of a 35 stored start condition at a field station when the system returns to its normal condition results in relays SAP and SA being picked up in sequence in the order named for marking the cycle as one for the transmission of indications.

40 *Transmission of controls.*—It will be assumed that the system is initiated as above described and that step-by-step operation occurs in synchronism at the control office and at the two stations illustrated, in the manner previously 45 discussed. It will also be assumed that the repeater station responds to a code combination of (+) (-) and that the regular station responds to a code combination of (-) (+).

45 It has already been explained that the first 50 or conditioning impulse applied to the line circuit is (+) to mark the cycle as one for the transmission of controls. The second impulse is selected when relay IV picks up its contacts during the first "off" period. In the assumed example, the picking up of relay IV closes a circuit 55 for positioning relay CS to the right which extends from (B+), code jumper 51, front contact 53 of relay CD, front contact 14 of relay IV, back contacts 15 and 16 of relays 2V and 3V respectively and winding of relay CS, to (CN).

With relay CS positioned to the right during the first "off" period, the next impulse (first "on") is (+) due to a circuit closed from the (+) terminal of battery B, contact 16 in its right 65 hand position, front contact 11 of relay S, winding of relay F, back contact 12 of relay EP, control line conductor, winding of relay F¹, back contact 150 of relay CK², return line conductor and contact 13 of relay CS in its right hand position to the (-) terminal of battery B.

70 This impulse positions relay F¹ to the right which closes a circuit for positioning relay CS¹ to the right extending from (B+), contact 165 of relay F¹ in its right hand dotted position, front 75

contact 166 of relay SA¹, front contact 172 of relay CK¹ and winding of relay CS¹, to (CN). Relay CS¹ positioned to the right applies a (+) impulse to control line¹ over a circuit extending from the (+) terminal of battery B¹, contact 152 of relay CS¹ in its right hand position, front contact 154 of relay CK¹, winding of relay F², back contacts 177, 155 and 156 of relays LV¹, 3V¹, and 2V¹ respectively, front contact 151 of relay IV¹, back contact 159 of relay CK², back contact 161 of relay VP¹, control line¹, winding of relay F³, back contact 250 of relay LO², back contact 350 of relay LO³, return line¹ and contact 151 of relay CS¹ in its right hand position to the (-) terminal of battery B¹.

This impulse repeated to control line¹ positions relays F² and F³ to the right. Relay F² closes a circuit for positioning relay 1PT¹ to the right which extends from (B+), contact 175 of relay F² in its right hand dotted position, back contact 176 of relay LO¹, front contact 178 of relay CK¹, front contact 179 of relay FP¹, back contacts 180 and 181 of relays 3V¹ and 2V¹ respectively, front contact 182 of relay IV¹ and winding of relay 1PT¹, to (CN). Relay F³ closes a circuit for positioning relay 1PT² to the right which extends from (B+), contact 260 of relay F³ in its right hand dotted position, front contacts 261 and 265 of relays SA² and FP² respectively, back contact 266 of relay LO², back contacts 267 and 268 of relays 3V² and 2V² respectively, front contact 269 of relay IV² and winding of relay 1PT², to (CN).

The second station selecting impulse applied to the control line is selected when relay 2V is picked up during the second "off" period. This impulse is (-) because relay CS is positioned to the left over a circuit extending from (B-), code jumper 52, front contact 54 of relay CD, front contact 15 of relay 2V, back contact 16 of relay 3V and winding of relay CS, to (CN). The actuation of contacts 10 and 13 of relay CS to their left hand dotted positions reverses the current flow over the control line circuit from that previously described in connection with the first impulse, so that relays F and F¹ are positioned to the left. Relay F¹ closes a circuit for positioning relay CS¹ to the left extending from (B-), contact 165 of relay F¹ in its left hand dotted position, front contacts 166 and 172 of relays SA¹ and CK¹ respectively and winding of relay CS¹ to (CN). The positioning of contacts 151 and 152 of relay CS¹ to their left hand dotted positions reverses the current flow in the control line¹ so that relays F² and F³ are positioned to the left.

Relay F² closes a circuit for positioning relay 2PT¹ to the left which extends from (B-), contact 175 of relay F² in its left hand dotted position, back contact 176 of relay LO¹, front contact 178 of relay CK¹, front contact 179 of relay FP¹, back contact 180 of relay 3V¹, front contact 181 of relay 2V¹ and winding of relay 2PT¹, to (CN). Relay F³ closes a circuit for positioning relay 2PT² to the left extending from (B-), contact 260 of relay F³ in its left hand dotted position, front contacts 261 and 265 of relays SA² and FP² respectively, back contact 266 of relay LO², back contact 267 of relay 3V², front contact 268 of relay 2V² and winding of relay 2PT², to (CN).

With relay 1PT¹ positioned to the right and relay 2PT¹ positioned to the left in response to the (+) (-) code as above described, the circuit for the third impulse is completed through

the contacts of these two relays to the switch machine relay SMR¹. Since relay 1PT² is positioned to the right and relay 2PT² is positioned to the left, the circuit for switch machine relay SMR² is not complete during the third impulse. It will be obvious that additional pilot relays can be provided for making up the circuits to the control relays at only a single station, which station responds to the station selecting code when the size of the system is increased, all in a manner similar to the making up of these circuits in the typical example just described.

In the event that code jumper 51 is connected in its dotted line position to (B-) and code jumper 52 is connected in its dotted line position to (B+), then relay CS is positioned to the left on the first station selecting step and to the right on the second station selecting step for providing a station selecting code of (-) (+). This positions relay F¹ to the left on the first step and to the right on the second step for positioning relay CS¹ to the left and right on the first and second steps respectively. This results in positioning relays F² and F³ to the left and right on the first and second steps respectively, so that relays 1PT¹ and 2PT¹ are positioned to the left and right respectively. Similarly relays 1PT² and 2PT² are positioned to the left and to the right respectively. Relays 1PT¹ and 2PT¹ in these positions do not complete circuits to the control relays, of which relay SMR¹ is typical, but relays 1PT² and 2PT² complete such control circuits.

With the station in Fig. 3A selected, the third impulse is determined by the position of switch machine lever SML in the control office, which in turn determines the position to which relay SMR¹ will be actuated at the repeater station. For example, with lever SML in its right hand normal position a circuit is closed for positioning relay CS¹ to the right which extends from (B+), contact 56 of lever SML in its right hand position, front contact 55 of relay CD, front contact 16 of relay 3V and winding of relay CS, to (CN). This applies a (+) impulse to the control line for positioning relay F¹ to the right which in turn positions relay CS¹ to the right. This applied a (+) impulse to control line¹ for positioning relays F² and F³ to the right. Relay F³ is not effective because the station illustrated in Fig. 4 has not been selected, but relay F² closes a circuit for actuating relay SMR¹ to the right which extends from (B+), contact 175 of relay F² in its right hand dotted position, back contact 176 of relay LO¹, front contacts 178, 179 and 180 of relays CK¹, FP¹, and 3V¹ respectively, contact 183 of relay 1PT¹ in its right hand position, contact 184 of relay 2PT¹ in its left hand dotted position and winding of relay SMR¹ to (CN). Relay SMR¹ with its contact 185 positioned to the right closes a circuit for operating the switch machine for placing the track switch in its normal position.

In the event that lever SML is in its left hand dotted reverse position, then (B-) is connected through contact 56 in its left hand dotted position and over the above described circuit for actuating relay CS to the left. This applies a (-) impulse to the control line circuit which actuates relay F¹ to the left. This actuates relay CS¹ to the left for applying a (-) impulse to the control line¹ circuit for actuating relays F² and F³ to the left. Contact 175 of relay F² in its left hand dotted position closes a circuit from (B-) over the previously described path

for operating relay SMR¹ to the left, which in turn places the track switch in its reverse locked position.

In the event that the station illustrated in Fig. 4 is selected by a station selecting code of (−) (+) impulses, then the third impulse determined by the switch machine lever in the control office, which is associated with this station, is effective to position relay SMR² to the right or left over a circuit which extends through contact 270 of relay 1PT² in its left hand dotted position and contact 271 of relay 2PT² in its right hand position, in a manner which is similar to that described in connection with the operation 15 of the corresponding relay at the repeater station.

The above examples indicate how two stations are selected, one having a station selecting code of (+) (−) and the other a code of (−) (+) during two steps of the cycle. It will be obvious that four stations can be selected during these two steps of the cycle by making use of the two additional combinations (+) (+) and (−) (−). In other words, code jumpers 51 and 52 in the control office can be connected in any one of their four possible combinations for selecting any one of four stations, each combination controlling the first two impulses of the cycle in accordance with the particular combinations selected by the particular CD relay which is picked up at the beginning of the cycle. Similarly, these four stations are selectable by having the two pilot relays at each station positioned in all four of their possible positions for completing circuits which are effective on the following steps to control local control relays such as relays SMR¹ and SMR².

It will be understood that additional levers will be provided in the control office associated with each station for controlling the signals at the selected station and signal control relays will be provided at each station for controlling these signals in accordance with the code combinations received from the control office. This additional circuit arrangement has been omitted, since it is believed that the typical example illustrating the switch machine control is sufficient for an understanding of the complete operation.

Automatic start.—When a change in condition occurs at a field station the change relay is dropped to initiate the system into a cycle of operations. If the change occurs at the repeater station, relay CH¹ is dropped for picking up relay LO¹ over a circuit extending from (+), back contact 202 of relay SAP¹, back contact 203 of relay CK¹, upper winding of relay LO¹ and back contact 204 of relay CH¹, to (−). Relay LO¹ closes a circuit for positioning relay CS¹ to the left which extends from (B−), back contacts 205, 206, and 207 of relays 1V¹, 2V¹, and 3V¹ respectively, conductor 201, front contact 176 of relay LO¹, back contact 172 of relay CK¹ and winding of relay CS¹, to (CN).

Relay CS¹ in its left hand position closes a circuit for picking up relay CK² which extends from (+), back contact 171 of relay SA¹, contact 186 of relay CS¹ in its left hand dotted position, back contact 187 of relay CK¹ and lower winding of relay CK², to (−). Relay CK² closes a stick circuit for itself extending from (+), back contact 168 of relay SAP¹, back contact 169 of relay CK¹, front contact 188 and upper winding of relay CK², to (−). This stick circuit is maintained complete until the end of the cycle be-

cause relay SA¹ closes its front contact 171 before relay SAP¹ opens its back contact 168.

Relay CK² closes its front contact 150 for energizing the control line with a (−) impulse over a circuit extending from the (+) terminal of battery B¹, contact 151 of relay CS¹ in its left hand dotted position, front contact 150 of relay CK², winding of relay F¹, control line conductor, back contact 12 of relay EP, winding of relay F, back contact 11 of relay S, return line conductor and contact 152 of relay CS¹ in its left hand dotted position to the (−) terminal of battery B¹. Current flowing over this circuit is effective to position relays F¹ and F to the left. The operation of relays F¹ and F close the previously described pick up circuits for relays FP¹ and FP respectively, after which relays SA¹, SAP¹, SA and SAP are picked up as previously described.

Relay CK in the control office is picked up over a circuit extending from (B−), contact 57 of relay F in its left hand dotted position, back contact 58 of relay SAP and upper winding of relay CK, to (B+). Relay CK closes a stick circuit for itself extending from (+), front contacts 59 and 60 in multiple of relays FP and SA respectively, front contact 61 and lower winding of relay CK, to (−). Since relay SA maintains its front contact 60 picked up until the end of the cycle relay CK remains stuck up throughout this cycle. The picking up of back contacts 20 and 22 of relay CK opens the pick up and stick circuits of relay S for a purpose which will be described in connection with stored office and indication start conditions. The picking up of back contact 62 of relay CK prevents the picking up of any CD relay.

Since this is the conditioning "on" period, the picking up of relays FP, SAP, FP¹, and SAP¹ cause relays VP and VP¹ to be picked up as previously described. Since relay LO¹ is picked up, the opening of its back contact 153 disconnects the control line¹ from the return line¹, so that any other station farther out the line will be ineffective to energize the line circuit, when such a station has new indications to transmit during a cycle used for the transmission of indications by the repeater station. In other words, the picking up of back contact 153 of relay LO¹ locks out all inferior stations. A stick circuit is closed for relay LO¹, when relay SA¹ picks up, which extends from (+), front contact 208 of relay SA¹, back contact 209 of relay CK¹, front contact 210 and lower winding of relay LO¹, to (−). This stick circuit maintains relay LO¹ energized until the end of the cycle.

The picking up of relays SA, SAP, and VP in the control office cause relays E and EP to be picked up in the manner described in connection with the control cycle. Relay EP deenergizes the control line at back contact 12 to mark the beginning of the first "off" period. The step-by-step and impulsive operations continue in the same manner as described in connection with the transmission of controls, as far as impulsive the line is concerned. In this instance, however, the control line is energized by battery B¹ at the repeater station instead of by battery B in the control office. This condition is clearly indicated in Fig. 1D showing relays F and F¹ energized by battery B¹ connected to the line circuit. This figure also shows batteries B¹ and B² connected to the return line¹ with the control line¹ open. This open point is at back contact 153 of relay LO¹ as previously mentioned.

In the event that the regular station illustrat-

ed in Fig. 4 initiates the system, the dropping of relay CH^2 closes a circuit for picking up relay LO^2 which extends from (+), back contact 272 of relay SAP^2 , back contact 273 of relay CK^3 , upper winding of relay LO^2 and back contact 274 of relay CH^2 , to (-). The picking up of back contact 266 of relay LO^2 renders the local control circuits ineffective and the picking up of contact 250 closes a circuit for energizing the control line¹ with a (-) impulse extending from the (+) terminal of battery B^2 , contact 251 of relay CS^2 in its left hand position, front contact 250 of relay LO^2 , winding of relay F^3 , control line¹, back contacts 158, 157, 156, 155 and 171 of relays CK^2 , IV^1 , $2V^1$, $3V^1$, and LV^1 respectively, winding of relay F^2 , back contacts 154 and 153 of relays CK^1 and LO^1 respectively, return line¹ and contact 252 of relay CS^2 in its left hand position to the (-) terminal of battery B^2 . Current in this circuit positions relays F^3 and F^2 to the left.

Relay F^3 causes the picking up of relays FP^2 , SA^2 and SAP^2 in the previously described manner. The picking up of relay SA^2 closes a stick circuit which maintains relay LO^2 energized throughout this cycle and which extends from (+), front contact 275 of relay SA^2 , back contact 276 of relay CK^3 , front contact 277 and lower winding of relay LO^2 , to (-). The picking up of back contact 250 of relay LO^2 locks out other stations farther out the line.

This energization of control line¹ marks the beginning of the conditioning "on" period by energizing line relays F^2 and F^3 . Relay F^2 closes the previously described circuit for positioning relay CS^1 to the left extending from (B-) at contact 175 in its left hand dotted position. Relay CK^2 is picked up and stuck up as previously described in connection with the initiation of the system from the repeater station. The picking up of contact 159 of relay CK^2 energizes the control line circuit with (-) current because relay CS^1 is in its left hand position. Relays F^1 and F^2 are energized as before, after which relays FP , CK , SA , and SAP in the control office are picked up. Relays E and EP pick up to mark the end of the conditioning "on" period as previously described.

It will thus be seen that the control line circuit extending from the repeater station to the office is energized with a (-) impulse when the system is initiated at the repeater station. A similar condition exists and in addition the control line¹ circuit extending from the regular station to the repeater station is energized with a (-) impulse when the system is initiated at the regular station. In the first instance the polarity of each impulse transmitted after the system is initiated at the repeater station, is determined by the station code combination and the indications associated with the repeater station. When the system is initiated at the regular station, the impulses transmitted during succeeding steps of the cycle are determined in accordance with the code combination and the indications associated with the regular station.

Impulse repeating operation.—It is believed desirable to give a brief summary of the impulse repeating operation during the transmission of controls, after which a brief outline of the impulse repeating operation during the transmission of indications will be given. It will be recalled that during a control cycle, relay CK^1 at the repeater station is picked up and relay CK^2 remains down. This is determined by the conditioning impulse applied to the control line

being (+). The end of the "off" periods and the beginning of the "on" periods are marked off by the dropping of relay EP in the control office, while the end of the "on" periods and the beginning of the "off" periods are marked by the picking up of relay EP which energizes and deenergizes respectively the control line.

In response to the energization of the control line at the beginning of the "on" periods, relay VP^1 at the repeater station is shifted and in response to the deenergization of the control line at the beginning of the "off" periods, a stepping relay is picked up. The shifting of the VP relay in response to the energization of the control line repeats this condition by energizing the control line¹ and the picking up of the stepping relay in response to the deenergization of the control line repeats this condition by deenergizing the control line¹. Since relays F^1 and FP^1 must pick up and relay VP^1 must shift during an "on" period before the control line¹ is energized to start the "on" period in this line, the energization of the control line¹ lags behind the energization of the control line by the time required to operate these three relays. Since relays F^1 and FP^1 must drop and the stepping relay must pick up in response to the deenergization of the control line before the control line¹ is deenergized, this deenergization of control line¹ lags behind the deenergization of the control line by the time required for these three relays to operate.

During the transmission of indications, relay CK^1 at the repeater station is down and relay CK^2 is picked up (as previously pointed out), irrespective of whether the transmitting station is the repeater station or the regular station. This is due to the fact that the conditioning impulse applied to the control line is (-). Of course, when an indication cycle is initiated from the repeater station the control line¹ is not impaled because back contact 153 of relay LO^1 is picked up.

After the initiation of the system in the control office as above described, the control line is deenergized by the picking up of relay EP to mark the end of the "on" periods and the beginning of the "off" periods. The control line is energized by the dropping of relay EP to mark the end of the "off" periods and the beginning of the "on" periods. Since relay E is controlled in its operation by the response of the stepping relay bank in the control office, the control office acts as the driver for the impulse operation during an indication cycle as well as during a control cycle.

When indications are transmitted from the regular station requiring that the impulses be repeated, the control line¹ is deenergized in response to the shifting of relay VP^1 during the "on" periods and the control line¹ is energized in response to the picking up of a stepping relay during the "off" periods. This is just opposite to the operation during a control cycle, since during such a cycle the control line¹ is energized in response to the shifting of relay VP^1 and deenergized in response to the picking up of a stepping relay. This shift in the impulse operation during an indication cycle is brought about by the picking up of contacts 158, 159 and 160 of relay CK^2 . In other words, the control line¹ connected to contact 161 of relay VP^1 is transferred so that this line is energized through front contacts 161 and 159 of relays VP^1 and CK^2 respectively when the odd stepping relays are picked up and energized through back contact 161 and front con-

tact 160 when relay VP¹ is down and the even stepping relays are picked up.

Therefore, the energization and deenergization of control line¹ leads the energization and deenergization of the control line during an indication cycle, because the energization of the control line is in response to the operation of relay EP which responds to the operation of the stepping relay bank in the control office, while the energization and deenergization of the control line¹ is in response to the operation of the stepping relay bank at the repeater station and since these stepping relay banks operate in synchronism, a lag is introduced between the response at the repeater station which energizes and deenergizes the control line¹ and the response at the control office which energizes and deenergizes the control line. This lag is that introduced by the dropping of relay EP. This transfer of the lagging operation makes it possible to condition the circuits during the "off" periods and to close up the executing circuits at the sending end in advance of their closure at the receiving end when sending either way over the system, with impulse driving controlled in the office in both cases.

Transmission of indications.—It will first be assumed that the repeater station initiates a cycle as above described for the transmission of indications. It will be assumed that the code combination of this station is (+) (—) provided on the first two steps of the cycle as determined by the connection of jumpers 211 and 212 in Fig. 3B.

When stepping relay 1V¹ is picked up during the first "off" period a circuit is closed for positioning relay CS¹ to the right which extends from (B+), jumper 211, front contact 205 of relay 1V¹, back contacts 206 and 207 of relays 2V¹ and 3V¹ respectively, conductor 291, front contact 176 of relay LO¹, back contact 172 of relay CK¹ and winding of relay CS¹, to (CN). With relay CS¹ positioned to the right the control line circuit is energized with a (+) impulse during the next "on" period extending from the (+) terminal of battery B¹, contact 152 of relay CS¹ in its right-hand position, return line conductor, back contact 11 of relay S, winding of relay F, back contact 12 of relay EP, control line, winding of relay F¹, front contact 150 of relay CK² and contact 151 of relay CS¹ in its right-hand position to the (—) terminal of battery B¹.

With relay 2V¹ picked up during the second "off" period the above described circuit for relay CS¹ extends through front contact 206 of relay 2V¹ and jumper 212 to (B—). This positions relay CS¹ to the left so that the control line is energized during the next "on" period by a (—) impulse, due to the reversal of the connection to the control line circuit from battery B¹ at contacts 151 and 152.

With a (+) impulse applied to the control line circuit at the first step, relay F is positioned to the right which closes an indication receiving circuit for positioning relay 1PT to the right extending from (B+), contact 57 of relay F in its right hand dotted position, front contact 58 of relay SAP, back contact 63 of relay S, back contact 64 of relay EP, back contacts 65 and 66 of relays 3V and 2V respectively, front contact 67 of relay 1V and winding of relay 1PT, to (CN).

The second impulse positions relay F to the left which closes the above described circuit from (B—) at the contact 57 of relay F by way of front contact 66 of relay 2V to position relay 2PT to the left. With relay 1PT positioned to the right and with relay 2PT positioned to the left a cir-

cuit is closed for energizing station relay ST corresponding to the repeater station when relay 3V is picked up during the third "off" period. This circuit extends from (+), front contact 68 of relay 3V, contact 70 of relay 1PT in its right-hand position, contact 69 of relay 2PT in its left-hand position and winding of relay ST, to (—).

The next impulse after the station registration code applied to the line circuit is (+) or (—) as determined by the position of track relay T¹ of Fig. 3B. If the track is unoccupied relay T¹ is picked up so that a circuit is closed from (B—) at front contact 213 of relay T¹ and front contact 207 of relay 3V¹ for positioning relay CS¹ to the left. This applies a (—) impulse to the control line circuit which positions relay F to the left. With contact 57 of relay F in its left-hand dotted position, (B—) is connected by way of front contact 65 of relay 3V and front contact 71 of relay ST to the winding of relay IR, which positions relay IR to the left for deenergizing lamp OS as an indication that the track switch is unoccupied.

When the track switch is occupied, relay T¹ drops to connect (B+) to relay CS¹ for positioning this relay to the right which applies a (+) impulse to the control line circuit for positioning relay F to the right. Contact 57 of relay F in its right-hand dotted position connects (B+) by way of front contact 65 of relay 3V and front contact 71 of relay ST to relay IR for positioning this relay to the right. A circuit is now closed at contact 72 of relay IR in its right-hand dotted position for lighting lamp OS as an indication that the track switch is occupied.

It will be obvious that other indications, such as the position of the track switch, the clear and stop signal indications and the like, may be transmitted on additional steps of the indication cycle in the same manner described for the transmission of the track occupancy indications just described. It is believed obvious that additional stations can be registered in the control office by providing different code combinations in accordance with the connections of code jumpers such as 211 and 212 of Fig. 3B at these additional stations. It is also believed obvious that in systems of larger size additional code jumpers can be selected on additional steps of the cycle to provide additional code combinations.

In the event that the regular station illustrated in Fig. 4 is transmitting indications during a cycle, the first impulse applied to the control line¹ is (—) as determined by relay CS² being positioned to the left over a circuit extending from (B—), code jumper 278, front contact 253 of relay 1V², back contacts 254, 255, and 256 of relays 2V², 3V², and CK³ respectively and winding of relay CS², to (CN).

With relay CS² positioned to the left a (—) impulse is applied to the control line¹ extending from the (+) terminal of battery B², contact 251 of relay CS² in its left-hand position, front contact 250 of relay LO², winding of relay F³, control line¹, front contact 161 of relay VP¹, front contact 159 of relay CK², front contact 157 of relay 1V¹, back contacts 156, 155 and 177 of relays 2V¹, 3V¹, and LV¹ respectively, winding of relay F², back contacts 154 and 153 of relays CK¹ and LO¹ respectively, return line¹ and contact 252 of relay CS² in its left-hand position to the (—) terminal of battery B². This positions relays F³ and F² to the left.

Relay F² closes a circuit for positioning relay CS¹ to the left which extends from (B—), con-

tact 175 of relay F² in its left-hand dotted position, back contacts 176 and 172 of relays LO¹ and CK¹ respectively and winding of relay CS¹, to (CN). With relay CS¹ in its left-hand position a (—) impulse is applied to the control line circuit through contacts 151 and 152 as previously described. This positions relay F to the left for connecting (B—) at contact 57 of relay F in its left-hand dotted position to relay 1PT for 10 positioning this relay to the left.

When relay 2V² is picked up during the second "off" period a circuit is closed for positioning relay CS² to the right extending from (B+), code jumper 279, front contact 254 of relay 2V² 15 and over the remainder of the previously described circuit to relay CS². With relay CS² positioned to the right a circuit is closed for energizing the control line¹ circuit with a (+) impulse which extends from the (+) terminal of battery B², contact 251 of relay CS² in its right-hand dotted position, return line¹ conductor, back contacts 153 and 154 of relays LO¹ and CK¹ respectively, winding of relay F², back contacts 177 and 155 of relays LV¹ and 3V¹ respectively, 20 front contact 158 of relay 2V¹, front contact 160 of relay CK², back contact 161 of relay VP¹, control line¹, winding of relay F³, front contact 250 of relay LO² and contact 252 of relay CS² in its right-hand dotted position to the (—) terminal 25 of battery B².

This impulse positions relay F² to the right for closing the above-described circuit of relay CS¹, which extends in this instance from (B+) at contact 175 of relay F² in its right-hand dotted position. Relay CS¹ is positioned to the right to apply a (+) impulse from battery B¹ to the control line circuit for positioning relay F to the right, which connects (B+) at contact 57 of relay F in its right-hand dotted position through front contact 66 of relay 2V to the winding of relay 2PT for positioning this relay to the right.

With relay 1PT positioned to the left and relay 2PT positioned to the right a circuit is closed from (+) at front contact 68 of relay 3V, through contacts of relays 1PT and 2PT (not shown) for energizing the station relay which corresponds to the station illustrated in Fig. 4.

The transmission of indications from the regular station takes place in a manner similar to that described in connection with its station registering code. This transmission is determined by track relay T² positioning relay CS² to the right or left in accordance with contact 280 of relay T² in its dropped away or picked up condition respectively. Relay CS² in its right or left-hand position, impulses the control line¹ with a (+) or a (—) impulse respectively for positioning relay CS¹, which repeats the received impulse over the control line for positioning relay F which in turn connects (B+) or (B—) at its contact 57 through front contact 65 of relay 3V and the front contact of the station relay corresponding to the regular station, to an indication receiving relay similar to relay IR. It is not believed necessary to describe this operation in detail since it is the same as similar typical operations above described.

The system is restored to its normal condition at the end of the cycle in the same manner as described in connection with a control cycle, when relay EP remains picked up for a sufficient time to cause relays SA and SAP to release. Since this produces a long deenergization of the control line circuit, relays SA¹ and SAP¹ likewise release. 70 Relay CK² is deenergized when relay SA¹ drops

its front contact 171 which deenergizes the stick circuit of relay CK² for an interval of time before this stick circuit is again energized by relay SAP¹ dropping its back contact 168. Relay LO¹ is deenergized if the repeater station is transmitting by the dropping of front contact 208 of relay SA¹. Relay LO² is deenergized if the regular station is transmitting when relay SA² drops its front contact 275. 5

The control line¹ circuit is deenergized to drop relays F³, FP², SA², and SAP² when the regular station is transmitting, due to the picking up of back contact 177 of relay LV¹ at the repeater station during the last "off" period in the control line circuit. Since relay LV¹ is maintained 15 picked up until relay SAP¹ deenergizes its stick circuit, the control line¹ circuit remains deenergized for a sufficient time to drop relays SA² and SAP². This interval of time may of course be increased slightly to insure the dropping of relay SAP² by making relay LV¹ slow acting, so that the control line¹ circuit is deenergized for an additional interval of time after that required to drop relay SAP¹. 20

Stored office and field start conditions.—In the event that there are stored office and field start conditions existing at the end of a cycle the system functions to give preference to the field station. At the end of a control cycle, relay S is dropped when relay SA drops its front contact 24 30 and the stepping relays are dropped when relay SAP drops its front contact 29.

Since it is assumed that there is another SR relay picked up, due to a stored office start condition, a circuit is closed for picking up relay STR 35 when relay SAP closes its back contact 18. This circuit extends from (+) through a front contact of the picked up SR relay similar to front contact 17. Relay CS will be positioned to the right when the stepping relays close their back 40 contacts 14, 15, and 16.

When relay SA¹ at the repeater station drops its front contact 171, relay CK¹ is deenergized and when relay SAP¹ drops its contacts the stepping relays at the repeater station are deenergized. 45 Assuming that the repeater station has a stored start condition at this time, the dropping of back contact 202 of relay SAP¹ closes a circuit for picking up relay LO¹ and relay CS¹ is positioned to the left over the above-described circuit extending from (B—) at back contact 205 of relay 50 1V¹. Relay CK² is picked up when relay CS¹ closes its contact 186 in its left-hand dotted position.

The picking up of relay STR in the control office closes the circuit for picking up relay S. 55 With relay S picked up and with relay CK² picked up the following battery connection is applied to the control line circuit:—From the (+) terminal of battery B, contact 10 of relay CS in its right-hand position, front contact 11 of relay S, winding of relay F, back contact 12 of relay EP, control line conductor, winding of relay F¹, front contact 150 of relay CK² and contact 151 of relay CS¹ in its left-hand dotted position to the (+) terminal of battery B¹. From the (—) terminal 60 of battery B, contact 13 of relay CS in its right-hand position, return line conductor and contact 152 of relay CS¹ in its left-hand dotted position to the (—) terminal of battery B¹. Since like terminals of the control office and repeater station batteries are connected together in this circuit no current flow takes place over the control line. Therefore, relays F and FP do not pick up. 70

Relay SAP is picked up over a circuit extending from (+), back contact 26 of relay FP, front con- 75

tact 28 of relay S, back contact 27 of relay SA and winding of relay SAP, to (—). The picking up of relay SAP deenergizes relay STR at back contact 18 and relay STR drops after a comparatively long interval of time. The picking up of relay SAP closes a circuit for picking up relay CK which extends from (+), front contact similar to 17 of the storing relay which is picked up, front contact 18 of relay SAP, back contact 73 of relay SA, front contact 74 of relay STR and lower winding of relay CK, to (—). This circuit is effective before relay STR has time to drop its contacts. The picking up of relay CK deenergizes relay S at back contacts 20 and 22 and the dropping of relay S disconnects the control office battery from the control line circuit and connects the control line and return line conductors together at back contact 11.

The control line is now energized from the repeater station battery which positions relays F and F¹ to the left. Relays FP, FP¹, SA, SA¹, and SAP¹ are now picked up over circuits previously described. The picking up of relay FP closes a stick circuit for relay CK extending from (+), front contact 59 of relay FP, front contact 61 and lower winding of relay CK, to (—). Relay SA connects (+) at its front contact 60 to this stick circuit to maintain relay CK picked up throughout this cycle. The purpose of front contact 59 is so that contacts 60 and 73 of relay SA will not need to be of the make-before-break type.

Since relay S is down and relay CK is picked up in the control office and since relay CK² is picked up and relay CK¹ is down at the repeater station, the cycle is marked for the transmission of indications which occur in the manner previously described. It will be apparent that the regular station causes the same operation under the above conditions because the control line circuit is energized from battery B¹ in response to the initiation of the system from the regular station as well as from the repeater station.

Lock out.—Referring to Figs. 3A, 3B, and 4, it will be assumed that the repeater station and the regular station have new indications ready to transmit at the same time with the system in its normal condition. The dropping of relay CH² at the regular station picks up relay LO² over the previously described circuit. The picking up of relay LO² energizes the control line circuit¹ with a (—) impulse over the previously described circuit and relays F³, F², FP², and SA² are picked up as previously described. Relay F² positions its contacts to the left for positioning relay CS¹ to the left, after which relay CK² is picked up and stuck up by means of the previously described circuits.

The picking up of relay CK² energizes the control line circuit with a (—) impulse which positions relay F¹ to the left, after which relays FP¹, SA¹, and SAP¹ are picked up. The energization of the control line with a (—) impulse positions relay F to the left for initiating the indication cycle, all as previously described.

The picking up of back contact 202 of relay SAP¹ renders the pick-up circuit of lock-out relay LO¹ ineffective, so that the dropping of relay CH¹ after the picking up of relay SAP¹ prevents the repeater station obtaining access to the communication system. In other words, the picking up of relay SAP¹, or similar relays at other superior stations, is the dead line beyond which no station can break in and take the communication system away from an inferior station.

In the event that relay CH¹ drops its contact

204 for picking up relay LO¹ before this dead line is reached, then the control line¹ is deenergized at back contact 153 so that an inferior station such as the regular station illustrated in Fig. 4 is dropped out because the line circuit extending 5 back from a superior station to an inferior station cannot be energized. This results in relays F³, FP², SA², SAP², and LO² being dropped if they happen to be picked up at the time the superior station cuts in and takes possession of the communication system. In the event that all of the above-mentioned relays at the inferior station are not picked up at this time, those which are picked up will be dropped when the line circuit extending from a superior station to an inferior station is deenergized.

It will be understood that the system functions in the same manner when some station other than the station illustrated in Fig. 4 has new indications to transmit at the same time a station nearer 20 the control office has new indications ready for transmission. It will also be understood that the system functions as above irrespective of whether the stations involved are repeater stations or regular stations, since the lock-out relay such as 25 relay LO¹ at a repeater station opens up the line circuit back towards inferior stations and the lock-out relay such as relay LO² opens up the line circuit from a regular station back towards other inferior stations.

Only at the station obtaining access to the communication system, are the indication circuits effective. For example, when the repeater station maintains its lock-out relay LO¹ picked up, the indication conditioning circuit including conductor 201 is made effective at front contact 176 of relay LO¹. The indication conditioning circuit of an inferior station is rendered ineffective because the stepping relays do not operate to select the local indication circuits. At other stations 40 between the station which obtains access to the line and the control office, stepping takes place but at these stations the line cannot be interfered with because the associated lock-out relays are deenergized so that the continuity of the line circuit is maintained through these stations at back contacts similar to 250 of relay LO². In other words, although stepping takes place and the code selecting relays at such stations are actuated 50 the battery connection is not made to the line circuit at these stations because of open front contacts such as 250 of relay LO².

Having thus described one specific embodiment of a centralized traffic controlling system it is 55 desired to be understood that the particular arrangements illustrated are merely typical of applicant's invention and are not intended to show the exact circuit design necessary to carry out the features of the invention, but have been selected to facilitate in the disclosure rather than 60 to limit its scope and it is further to be understood that various modifications may be made and various adaptations and alterations may be applied to the specific form disclosed in order to 65 meet the various problems encountered in practice and that the system may be varied in the number of repeater and regular stations, the amount of apparatus installed at the particular field station and the number of steps provided 70 for station selection and registration, all without in any manner departing from the spirit or scope of the invention except as limited by the appended claims.

What I claim is:—

1. In a remote control system, a control office, 75

5 a plurality of field stations, a first line circuit extending from said office through a first plurality of said stations, a second line circuit extending from one of said first stations through a second plurality of said stations, means in said office for applying any one of several different series of current impulses to said first line circuit, means at one of said first plurality of stations responsive to said series of impulses for applying facsimiles thereof to said second line circuit, and means controlled by said impulses for transmitting messages both ways over said line circuits.

10 2. In a centralized traffic controlling system for railroads, a plurality of locations including a control office and a plurality of field stations, a first circuit connecting certain of said locations, a second circuit connecting other of said locations, traffic controlling devices at each of said stations, means in said office for applying any one of several different combinations of impulses of different electrical characteristics to said first circuit, means for automatically repeating said combinations of impulses into said second circuit, and means controlled by said impulses and said repeated impulses for transmitting messages both ways over said circuits for governing the operation of said devices and for indicating in the control office the conditions of said devices.

15 3. In a remote control system, a control office, a first field station and a second field station, a first line circuit and a second line circuit, step-by-step means at said office and at each of said stations all operated in synchronism by impulses of current applied to said line circuits regardless of their polarity, means including the step-by-step means at one of said stations for repeating the impulses from said first line circuit into said second line circuit, and station registering means at said stations selectively responsive at each step of the associated step-by-step means to different combinations of positive and negative impulses in said line circuits.

20 4. In a remote control system, a control office and a first plurality of field stations connected by a first line circuit, a second plurality of field stations connected to one of said first plurality of stations by a second line circuit, means for applying impulses to said line circuits, step-by-step mechanisms at each of said stations all operated substantially in synchronism by said impulses regardless of their polarity, means including said mechanisms for marking said impulses positive and negative, means for repeating the marking of said impulses from said second line circuit into said first line circuit, and station registering means in said office selectively responsive to said marked impulses.

25 5. In a remote control system, a control office, a plurality of field stations, a first line circuit connecting said office with a first station, a second line circuit connecting said first station with a second station, automatically controllable means in said office for applying a plurality of different series of impulses to said first line circuit, means at said first station responsive to said series of impulses for applying fac-similes thereof to said second line circuit, means at said stations for selecting the characteristics of said impulses, and station registering means in said office selectively responsive to the characters of the impulses of said series.

30 6. In a centralized traffic controlling system for railroads, a plurality of locations including a control office and a plurality of field stations, a

first circuit connecting certain of said locations, a second circuit connecting other of said locations, traffic indicating devices at said office associated with said stations, automatic controllable means in said office for applying any one of several different series of impulses to said first circuit, means for automatically repeating said impulses into said second circuit, means associated with said second circuit for characterizing said impulses and station registering means in said office selectively responsive to the character of said impulses for rendering said traffic indicating devices associated with one particular station effective to respond to succeeding impulses.

35 7. In a remote control system, a control office, a plurality of field stations, a first line circuit and a second line circuit, impulsive means in said office for applying a series of impulses to said first line circuit, impulsive means at one of said stations responsive to said impulses for applying a fac-simile of said impulses to said second line circuit, contacts at each of said stations automatically controllable in response to an automatic charge in an electrical circuit, and means controlled by said contacts for selecting the characteristics of said impulses to conform with a distinctive code call for the corresponding station and the positions of said contacts for that station.

40 8. In a remote control system, a control office, a plurality of field stations, a first line circuit connecting said office with a first station, a second line circuit connecting said first station with a second station, means in said office for applying a plurality of different combinations of impulses to said first line circuit, means at said first station for repeating said combinations of impulses to said second line circuit, means at each of said stations for governing the character of each impulse of the combinations applied to said first line circuit, and means responsive to the characteristic combinations of impulses in said first line circuit for registering said stations in said office.

45 9. In a remote control system, a control office, a plurality of field stations, a first line circuit connecting said office with a first station, a second line circuit connecting said first station with a second station, means in said office for applying a plurality of different combinations of impulses to said first line circuit, means at said first station for repeating said combinations of impulses to said second line circuit, means at each of said stations for governing the character of each impulse of the combinations applied to said first line circuit, and means responsive to the characteristic combinations of impulses in said first line circuit for registering said stations in said office and for transmitting indications from the registered station to the office.

50 10. In a remote control system, a first station and a second station connected by a first line circuit, a third station connected to said second station by a second line circuit, means for energizing said first line circuit with time spaced first order impulses of distinctive character, stepping means at said second station responsive to said first order impulses irrespective of their character, impulse storing means at said second station responsive to the character of said first order impulses, impulse repeating means at said second station controlled by said stepping means for energizing said second line circuit with time

spaced second order impulses, and means controlled by said storing means for governing the character of said second order impulses.

11. In a remote control system, a first station and a second station connected by a first line circuit, a third station connected to said second station by a second line circuit, means for energizing said first line circuit with time spaced first order impulses of distinctive character, stepping means at said second station responsive to said first order impulses irrespective of their character, impulse storing means at said second station responsive to the character of said first order impulses, impulse repeating means at said second station controlled by said stepping means for energizing said second line circuit with time spaced second order impulses, means controlled by said storing means for governing the character of said second order impulses, and means at said stations selectively responsive to said first and second order impulses.

12. In an impulse repeating system, a first line circuit and a second line circuit, means for applying a first series of impulses to said first line circuit, means responsive to said first series for applying a first fac-simile of impulses to said second line circuit, means for applying a second series of impulses to said first line circuit, means responsive to said second series for applying a second fac-simile of impulses to said second line circuit, means for rendering said first series leading with respect to said first fac-simile, means for rendering said second series lagging with respect to said second fac-simile, and means controlled by said leading and lagging impulses for transmitting messages both ways over said line circuits.

13. In a remote control system, a first field station and a second field station each having a bank of stepping relays, channel circuits selected by said banks of stepping relays, means responsive to a series of impulses received at said first station for sequentially operating the associated bank of stepping relays, means controlled in accordance with a code for determining the particular channel circuits to be effective for any one operation of said banks of stepping relays, means controlled at said stations for coding said impulses, and means controlled by the bank of stepping relays at said first station for transmitting a fac-simile of said impulses to said second station.

14. In a remote control system, a control office, a first field station and a second field station, a first line circuit and a second line circuit, a series of stepping relays at said first station, means at said office for applying a first plurality of impulses of current to said first line circuit, means controlled by said first plurality of impulses for sequentially operating said relays in synchronism with said first plurality of impulses, and means controlled by the contacts of the relays at said first station for repeating the impulses from said first line circuit into said second line circuit.

15. In a remote control system, a control office and a first plurality of field stations connected by a first line circuit, a second plurality of field stations connected to one of said first plurality of stations by a second line circuit, a series of stepping relays at said office and at each station connected to said first line circuit, means for applying a first plurality of coded impulses of current to said first line circuit, means controlled by said first plurality of im-

pulses for sequentially operating the relays at the office and stations connected to said first line circuit substantially in synchronism, means controlled at each step of the stepping relays in said office and at corresponding steps of the stepping relays at said stations for transmitting and receiving respectively a distinctive code carried by the impulse at that step, and means controlled by the contacts of the stepping relays at one of said first plurality of stations for repeating the impulses from said first line circuit into said second line circuit.

16. In a remote control system, a control office, a plurality of field stations, a first line circuit extending from said office through a first plurality of said stations, a second line circuit extending from one of said first stations through a second plurality of said stations, means in said office for applying any one of several different series of impulses of current to said first line circuit, receiving means included in said first line circuit at one of said first plurality of stations for receiving said impulses, storing means for storing said impulses, means controlled by said storing means for applying fac-similes thereof to said second stepping circuit, stepping relays at each of said stations operated sequentially and synchronously by said series and said fac-similes, and station selecting means selected by said stepping relays at said stations selectively responsive to said series and said fac-similes.

17. In a remote control system, a control office, a first field station and a second field station, a first line circuit and a second line circuit, step-by-step means at said first station, means for applying a first plurality of positive and negative impulses of current to said first line circuit, means controlled by said first plurality of impulses for operating said mechanism in synchronism with said first plurality of impulses, means controlled by the mechanism at said first station for repeating the impulses from said first line circuit into said second line circuit, and station selecting means at said stations selectively responsive to different combinations of positive and negative impulses in said line circuits.

18. In a remote control system, a control office and a first plurality of field stations connected by a first line circuit, a second plurality of field stations connected to one of said first plurality of stations by a second line circuit, step-by-step mechanisms at said office and at each station connected to said first line circuit, means for applying a first plurality of coded positive and negative impulses of current to said first line circuit, means controlled by said first plurality of impulses for operating the mechanisms at the office and stations connected to said first line circuit substantially in synchronism, means controlled at each step of the stepping relays in said office and at corresponding steps of the stepping relays at said stations for transmitting and receiving respectively a distinctive code carried by the impulse at that step, means controlled by the mechanism at one of said first plurality of stations for repeating the impulses from said first line circuit into said second line circuit, and station selecting means at said stations selectively responsive to different combinations of positive and negative impulses in said line circuits.

19. In a centralized traffic controlling system for railroads, a plurality of locations including a control office and a plurality of field stations, a first circuit connecting certain of said locations, a second circuit connecting other of said locations,

traffic controlling devices at each of said stations, means in said office for applying any one of several different combinations of impulses of different electrical characteristics to said first circuit, means for automatically repeating said combinations of impulses into said second circuit, means controlled by said impulses and said repeated impulses for transmitting messages both ways over said circuits, means controlled by said 5 messages for governing the operation and indicating the operated conditions of said traffic controlling devices and station selecting means at said stations selectively responsive to said combinations and said repeated combinations of impulses 10 for rendering said traffic controlling devices at one particular station effective to respond to succeeding impulses.

20. In an impulse system, an office, a plurality of stations, a first line circuit and a second line circuit, impulsive means in said office for energizing said first line circuit with a series of time-spaced impulses, impulsive means at a first one of said stations responsive to said impulses for applying a fac-simile of said impulses to said 25 second line circuit, a source of current in said office and a source of current at said first station, initiating means in said office and for initially energizing said first line circuit from the office source of current, initiating means at each of 30 said stations for initially energizing said first line circuit from the source of current at said first station, means responsive to the energization of said first line circuit from either of said sources for controlling the operation of said impulsive 35 means, and means responsive to the concomitant operation of said initiating means for momentarily preventing the operation of said impulsive means by momentarily preventing the energization of said first line circuit.

40 21. In an impulse system, an office, a plurality of stations, a first line circuit and a second line circuit, impulsive means in said office for applying a series of impulses to said first line circuit, impulsive means at one of said stations 45 responsive to said impulses for applying a fac-simile of said impulses to said second line circuit, a source of current in said office and at said first station, means responsive to said impulses for transmitting messages both ways over said 50 line circuits, initiating means in said office for initially energizing said first line circuit from the office source of current, initiating means at each of said stations for initially energizing said first line circuit from the source of current at 55 said first station, means responsive to the energization of said first line circuit from either of said sources for controlling the operation of said impulsive means, and means responsive to the concomitant operation of said initiating means 60 for permitting the transmission of messages only one way over said line circuits by momentarily preventing the energization of said first line circuit.

65 22. In an impulsive system; an office and a plurality of stations; a first line circuit connecting said office with a first one of said stations; a second line circuit connecting said first station to a second one of said stations; means in said office for impressing a series of time spaced 70 primary impulses of distinctive character on said first line circuit; step-by-step mechanisms in said office and at said first station each caused to take one step in response to each of said primary impulses; character determining means in said office for determining on each

step the character of the next primary impulse; primary storing means controlled by said primary character determining means during the time space preceding each primary impulse, said primary storing means controlling the character 5 of the next succeeding primary impulse; impulse receiving and repeating means at said first station distinctively responsive to the character of said primary impulses; means controlled by said impulse receiving and repeating means for controlling the impression of a series of time spaced secondary impulses of distinctive character on said second line circuit; step-by-step mechanism at said second station caused to take one step in response to each of said secondary impulses; secondary character determining means at said first station controlled by said impulse receiving and repeating means for determining on each step the character of the next secondary impulse; and secondary storing means controlled by said secondary character determining means during the time space preceding each secondary impulse, said secondary storing means controlling the character of the next succeeding secondary impulse. 10 15 20 25

28. In a code transmitter; an office and a plurality of stations; a first line circuit connecting said office with a first one of said stations; a second line circuit connecting said first station to a second one of said stations; means in said office for impressing a series of time spaced primary impulses of distinctive character on said first line circuit; step-by-step mechanisms in said office and at said first station each caused to take one step in response to each of said primary impulses; character determining means in said office for determining on each step the character of the next primary impulse; primary storing means controlled by said primary character determining means during the time space preceding each primary impulse, said primary storing means controlling the character of the next succeeding primary impulse; impulse receiving and repeating means at said first station distinctively responsive to the character of said primary impulses; means controlled by said impulse receiving and repeating means for controlling the impression of a series of time spaced secondary impulses of distinctive character on said second line circuit; step-by-step mechanism at said second station caused to take one step in response to each of said secondary impulses; secondary character determining means at said first station controlled by said impulse receiving and repeating means for determining on each step the character of the next secondary impulse; secondary storing means controlled by said secondary character determining means during the time space preceding each secondary impulse, said secondary storing means controlling the character of the next succeeding secondary impulse; and means controlled by said primary and secondary impulses for transmitting code messages over said line circuits. 30 35 40 45 50 55 60 65

24. A remote control system of the character described for transmitting indications from any one of a plurality of field stations to a control office comprising, a first line circuit connecting said control office to a repeater field station, a second line circuit connecting another field station to said repeater field station, means including a battery at each field station for intermittently energizing said line circuits, step-by-step means in the control office and at each field station 70 75

tion operated substantially in synchronism to take one step in response to each de-energization of said line circuits, pole-changing means in said line circuits at each field station for reversing the 5 polarity of energization of the associated line circuit, circuits controlled by said step-by-step means at each field station for controlling the associated pole-changing means successively during each de-energization of said line circuits in

accordance with indications to be transmitted, means at said repeater station for repeating the polarity of energization of said second line circuit into said first line circuit, and indicating means in the control office governed by its step-by-step means for responding to the polarity of energization of said line circuits for each step. 5

WINFRED T. POWELL.
